UNITED STATES PATENT OFFICE.

JOSEPH B. FISCHER, OF CHICAGO, ILLINOIS, ASSIGNOR OF ONE-HALF TO
ERNEST A. TESCH, OF CHICAGO, ILLINOIS.

FISHING-ROD.

No. 813,492.

Specification of Letters Patent.

Patented Feb. 27, 1906.

Application filed May 15, 1905. Serial No. 260,420.

To all whom it may concern:

Be it known that I, JOSEPH B. FISCHER, a citizen of the United States, residing at Chicago, in the county of Cook and State of Illinois, have invented certain new and useful Improvements in Fishing-Rods, of which the following is a specification.

This invention relates to improvements in fishing-rods.

10 The especial object of the improvements described in this application is to produce a fishing-rod composed of a plurality of tubular steel rods, each rod or section being of uniform cross diameter throughout its length 15 and a series of sections adapted to slide telescopically one within the other.

A further object is to produce a rod in which the tubular sections can be partially or entirely extended relative to each other or to 20 the handle and will be automatically locked or held in their extended relation.

25 A further object is to provide in a fishing-rod means for interlocking two joints in a simple and effective manner and one which will hold the sections firmly without possibility of working loose or being affected by moisture or temperature.

30 A still further object is to produce a rod having a reversible handle, whereby the gripping portion may be either above or below the reel attachment and a handle which will be free from the possibility of having the parts expand or shrink under the influence of the weather or will be subjected to wetting and 35 subsequent drying out.

Other objects of general utility are secured through my invention and same need not be specifically referred to herein.

In the accompanying drawings I have 40 shown a preferred embodiment of my invention in the following views.

Figure 1 is an elevation of a fishing-rod constructed according to my invention, showing the handle and two joints. Fig. 2 is a view similar to Fig. 1, but showing the grip of the handle reversed and a portion of the latter broken away to clearly disclose the inner construction of the handle. Fig. 3 is a view, partly in elevation and partly in section, 45 of two tubular sections or joints of my improved rod, a portion of one of the joints being broken away to show the method of interlocking the joints. Fig. 4 is a longitudinal sectional view, on an enlarged scale, showing

the peculiar spring-sleeve which forms an important element of the interlocking means of my invention. 55

Referring to the drawings in detail, A represents the grip portion of the handle of my improved rod, and same may be formed of 60 cork, celluloid, or any other suitable material. This grip is fitted closely over a tube B, within which are secured two spacing or guide rings b' b''. Fitted to one end of the tube B is a second tube C, in the face of which is formed a longitudinal recess or depression c', which is adapted to receive the seat of an ordinary reel, the same not being shown herein, as it forms no part of this invention. Slidably mounted on the tube C are two rings 65 c'' c'', which are adapted to hold the base of the reel in its seat on the tube C. One end of the tube C is formed flaring, as at c'', to provide an overhanging flange, within which is received one end of the grip A, thus forming 70 protection for the edge of said grip. The opposite end of the tube C is provided with a spacing or guide ring c''. In practice the tube B will be brazed or otherwise secured rigidly to the tube C, thus forming a continuous member. 75

It will be understood that the spacing or guide members b', b'', and c'' are centrally perforated, or, in other words, are rings. Passing through these rings is a rod D, which, as 85 shown, forms a receiver for one of the telescopic sections of the rod to be described. Rigidly fixed in the lower end of the tube D is a screw-plug d', the threaded portion of 90 which projects downwardly from the end of the tube D, as shown in Fig. 2. Rigidly secured on the rod D is a thimble d'', in which bearings d'' d'' are provided for the tube D, and the lower end of said thimble is flared outwardly, as at d'', thus forming overhanging flange for the grip A. Secured to the lower end of the rod D is a detachable thimble d'', in which is secured a threaded bearing d'' to receive the threaded portion of the screw-plug d''. 95

100 It will be apparent from the foregoing description that if it be desired to change the position of the grip A, as shown in Fig. 2, to the position shown in Fig. 1, it will be necessary only to unscrew the thimble d'' from the screw-plug d' and slide the grip A, the tube B, and the tube C from the rod D, invert said removed tubes and restore them to the rod D

and replace the thimble d^6 , it being understood that the thimble d^2 remains in its original position on the rod D and forms a stop for the handle element C.

- 5 It will be noted that the construction described provides a handle composed of hollow elements, in which bearing-rings are fixed to give sufficient rigidity and strength to the parts and also to provide guides for the rod D.
 10 In practice the tubes B and C may be made of aluminium or brass or other non-corrosive metal, or the bearing-rings alone may be made of such metal, thus permitting ready removal of the parts from the rod D.
 15 Secured within the outer end of the rod D is a bushing-ring d^8 , which is brazed in place and serves as a stop for the rod-section F, that is telescopically mounted within the rod D. Each section F is supplied with one of these 20 rings d^8 at its outer end. To the outer side of each of the sections D and F is secured a line-guide d^9 .

The telescopic sliding or extensible sections of my improved rod are hollow tubes of 25 suitable material, formed without seams and of uniform cross-diameter throughout their entire lengths, one of said sections being shown and designated F in Figs. 3 and 4.

To the lower end portion of each of the telescopic sections F is secured a sleeve G, one 30 end of said sleeve being attached to the rod F and the other end loose on the rod. The sleeve G is made of suitable spring metal having more or less resiliency, and through the 35 walls of same are cut semispiral openings g' , and said sleeves are upset, thus giving them a slight convexity throughout the greater portion of their length, as clearly indicated in Fig. 4. Coinciding with the grooves 40 g' in the sleeve G, I prefer to cut similar slots f' through the walls of the rods F, so that if any particles or dirt should get between the adjacent walls of the rods F and their respective sleeves G the same could fall through 45 the slots f' into the bore of the rods F, and thus be entirely removed from the sections. In practice the spring-sleeves G will be of sufficient diameter to effect a close fit between the rod-sections, so that the expansion of the 50 sleeve will exert sufficient pressure on the walls of the rods to form an interlock between said rods, which will hold each section in any position to which it may be adjusted by the user of the device, at the same time permitting 55 the sections to be pushed entirely in or pulled out when sufficient force is exerted by the user. The ends of the sleeves G will strike against the inner edges of the bushing-rings d^8 , thus positively limiting the outward 60 and inward movements of each of the rod-sections when they have been extended or retracted to their full limit.

It will be noted that by having each of the rod-sections F of uniform cross-diameter 65 throughout its entire length I am enabled

thereby to obtain a relatively greater strength in the rod-sections than where they are made tapering, as is common in most telescopic rods with which I am familiar. It should also be noted that the long bearing or interlocking joint between the rod-sections, which is effected by the spring-sleeve G, gives stability to the rod when extended that would not be possible if the bearing was restricted to a collar or ring.

In manufacturing these rods it is the custom to apply the sleeves G to the rods F in the position they are to remain, and then cut the slots $g' f'$ through both the sleeves and the rods.

Having thus described my invention, what I claim as new, and desire to obtain by Letters Patent, is—

1. In a fishing-rod, a plurality of telescopically-mounted metal tubular sections each 85 of uniform cross-diameter throughout its length, means for interlocking said sections consisting of a spring-sleeve arranged at one end of each section and having the portion between its ends of greater cross-diameter 90 than at its ends and adapted to expand against the inner walls of the outer section.

2. In a fishing-rod, a plurality of telescopically-mounted metal tubular sections, means for interlocking said sections consisting of a 95 tubular spring-sleeve arranged at one end of each section and having slots cut longitudinally therein, the ends of said slots being closed and said sleeve adapted to expand against the inner walls of the outer section.

3. In a fishing-rod, a tubular rod of uniform cross-diameter throughout its length, a handle reversibly mounted on said rod and consisting of a grip portion and a reel-seat portion, said rod extending entirely through 105 said handle, a thimble fixed on said rod, and a thimble removably secured to one end of said rod, said fixed and removable thimbles forming end bearings for said grip and reel-receiving portions respectively.

4. In a fishing-rod, a tubular rod of uniform cross-diameter throughout its entire length and a threaded plug inserted in one end of said rod, a hollow handle reversibly mounted on said rod and consisting of a grip portion and a reel-seat portion, said rod extending entirely through said handle, collars slidably mounted on said reel-seat portion, a thimble fixed on said rod and having its edges flared outwardly, a thimble having a threaded engagement with said plug, having its ends outwardly flared, said fixed and removable thimbles forming end bearings and means for protecting the edges of said reel and grip portions respectively.

5. In a fishing-rod, a plurality of telescopically-mounted metal tubular sections, means for interlocking said sections consisting of a spirally-slotted tubular spring-sleeve arranged at one end of each section, a and adapt-

ed to expand against the inner walls of the outer section.

6. As a means for frictionally interlocking two tubular rods, a sleeve composed of spring metal having a plurality of helical slots formed therein, said slots extending for a portion only of the length of said sleeve, and the slotted portion of said sleeve being of greater cross-diameter than the unslotted portion.
7. A rod composed of a plurality of metal tubes telescopically arranged, each of uniform cross-diameter throughout its entire length, and each provided with a tubular

sleeve of spring metal, and with an internal collar adapted to serve as a stop for the tube 15 passing through said collar, said sleeve having longitudinal slots formed therein between its ends, and the slotted portion being of greater cross-diameter than the ends.

In testimony whereof I affix my signature 20 in presence of two witnesses.

JOSEPH B. FISCHER.
